by William B. Haas
Attest

UNITED STATES PATENT OFFICE.

BERTRAM J. GRIGSBY, OF CHICAGO, ILLINOIS.

ELECTRIC FUSE.

Application filed January 23, 1918. Serial No. 219,165.

To all whom it may concern:

Be it known that I, BERTRAM J. GRIGSBY, a citizen of the United States, and a resident of Chicago, in the county of Cook and State 5 of Illinois, have invented certain new and useful Improvements in Electric Fuses; and I do hereby declare that the following is a full, clear, and exact description thereof, reference being had to the accompanying 10 drawings, and to the characters of reference marked thereon, which form a part of this specification.

This invention relates to improvements in electrical thermal fuses which are designed to 15 open circuits in which the fuses are connected upon the passage of an abnormal current through the circuit; the fuse embracing a link or element which is made of such character and such cross section as to break down 20 or fuse at a predetermined overload.

Among the objects is to provide, in a fuse of this character, means for causing a quick rupture of the fuse element when softened by the temperature of a predetermined 25 load current so as to effect a prompt cut out of the circuit and to prevent reestablishment of the circuit through parts of a fuse element which has been imperfectly ruptured.

A further object of the invention is to 30 produce an improved enclosed fuse of that kind in which the fuse element is enclosed in and protected by a covering, usually known as a cartridge, the improvements in this phase of the invention relating to means 35 for preventing injury to the cartridge by the gases generated therein, due to the rupture of the fuse element under heat.

The invention consists in the combination and arrangement of the parts shown in the 40 drawings and described in the specification, and is pointed out in the appended claim.

In said drawings,

Figure 1 is an axial section of a refillable fuse embodying my invention, showing the 45 manner of mounting the same on the base for connection in the line to be protected thereby.

Figure 2 is a cross section on the line 2—2 of Figure 1.

Figures 3 and 4 are axial sections showing, 50 other modifications.

Figure 5 is a cross section on the line 5—5 of Figure 4.

Figure 6 is an axial section showing a still further modification. 55

Figures 7 and 8 illustrate different designs of fuse links.

Referring first to the construction illustrated in Figure 1 of the drawings, 10 designates a fuse cartridge which comprises a cylindrical shell made of any suitable insulating material and 11, 11' designate end caps or ferrules which are applied over the open ends of the shell 10. Said cartridge may be seated in the terminal clips 12 which are fixed in any suitable manner to the insulating base 14 which supports the terminals 15 for connection to the line.

The said ferrules or end caps 11, 11' are made of current conducting material, such as brass or copper, and are included in the circuit to the fuse link 16 within the shell or cartridge 10. In the construction shown in Figure 1, one end of the fuse link is connected by a screw 17 directly to the head of ferrule 11. At the other end of the cartridge casing or shell is a current conducting sleeve or bushing 18 which fits closely within the shell or cartridge 10. It has at its outer end a radial flange 19 which is confined between the end or head of the adjacent cap or ferrule 11' and the end of the shell 10. The other end of said bushing 18 is turned inwardly to form a radial flange or shoulder 20 having a central opening through which one end of the fuse link 16 extends. Seated within said bushing 18 is a disc 21 made of good conducting material, the disc being free to slide endwise of said bushing. Interposed between said disc and the flange or shoulder 20 of the bushing is a spiral expansion spring 22 which tends to force the disc 21 away from said flange 20. The end of the fuse link adjacent to said bushing 18 extends through the spring and through an opening 24 formed in said disc, and its extreme end is turned downwardly over the outer face of the disc and is secured to said disc by a screw 25. 20

By reason of the fact that one end of the fuse link is attached to the slidable disc 21, and the fact that the spring 22 is interposed 25

between the disc and the flange 20, the fuse link is held in a position which is readily removable for the purpose of replacing the fuse element.

between said disc and the flange or shoulder 20, said spring tends to force the disc away from said flange and exerts a pulling stress on the fuse link. This pulling stress is constant, and it serves, when the fuse link is ruptured to quickly separate the parts of said link at the sides of the rupture. This quick and effective separation of the parts of the fuse link serves to promptly open the circuit and to reduce to a minimum the time in which the fuse element or link is subjected to the fusing temperature; it being apparent that when the circuit is opened the thermal effect of the overload is arrested. Therefore, the prompt opening of the circuit at the sides of the rupture has the effect of lessening the accumulation of gases in the fuse chamber of the shell or cartridge due to the fusing of the metal. It will be observed moreover that as soon as the parts of the fuse link are separated at the sides of the point of rupture the spring 22, in forcing the disc 21 away from the flange 20, has the effect of increasing the voluminal capacity of the shell so as to thereby reduce any pressure which has accumulated therein due to the generation of gases.

A feature of the construction described to be observed is that the opening 24 in the terminal disc 21, best shown in Figure 2, is of such size and shape as to limit or determine the cross section of the fuse element which may be used in the device. That is to say, the said opening is of a size to permit the passage therethrough of a fuse element of a certain thickness and width so that it becomes impossible to reload the fuse cartridge with a fuse element of greater than a predetermined cross section. Thus the danger of overloading the circuit is avoided.

In the construction shown in Figure 3, the shell 30 and the end caps or ferrules 31, 32 are generally like the similar parts shown in Figure 1, with the exception that the head of the ferrule 32 is provided with an opening through which the fuse link 33 extends, and with a recessed portion 34 to afford access to the holding screw 35 by which the adjacent end of the fuse link is attached to the ferrule 32. At its other end the fuse link is attached directly to the end of the cap or ferrule 31 by a screw 36. The opening in the recessed portion of the cap or ferrule 32 through which the fuse link extends serves, as does the opening 24 of the disc 21, to limit or determine the cross section of the fuse link used in connection with the cartridge.

Tension is normally exerted on said fuse link 33 by means of a contractile spring 37 which is hooked at one end 38 to engage an opening or a shoulder in the link and is attached at its other end, as by means of a holding rivet 39, to the shell 30 in any suit-

able manner. Said spring 37 performs the general function of the spring 22 before referred to in that it effects a quick separation of the parts of the link at the sides of a rupture caused by the fusing of the link. 70

In the construction shown in said Figure 3, the shell or cartridge is provided with one or more openings 40 which are covered by a transparent tube 41 made of mica or like material that is contained within the shell. Said openings 40 constitute windows through which the fuse link may be observed to determine whether or not it is intact. The said windows may be applied to the other forms of construction herein shown. 80

In the construction shown in Figure 4, the end terminal caps or ferrules 45 which are slipped over the ends of the shell 46, are provided with centrally recessed or depressed portions 47 to receive conducting discs 48, between which the fuse link 49 is stretched. The depressed heads are centrally apertured and the discs 48 close said apertures. Said fuse link is directly attached at one end, as by a screw 50, to one of said discs 48, and is connected to the other disc 48 by means of a contractile spring 51 suitably fastened at one end to said link and attached, as by a screw 52 to the adjacent disc 48. Said spring serves to quickly separate the parts of the fuse link at the sides of a rupture in the same manner as the springs heretofore described. Seated within said shell or cartridge 46, at the sides of the longitudinal center thereof are discs 53 which are peripherally flanged to afford a close seating bearing between the same and the shell. Said discs 53 are provided with central openings 54, best shown in Figure 5, which determine the dimensions of the fuse link extending therethrough. 100 105

In the operation of the device shown in Figure 4, when the fuse is ruptured the parts at the sides of the rupture are separated by the action of the spring 51 and the discs 48 fall away from the heads of the caps or ferrules 45. 110

In the construction shown in Figure 6, two springs 55 are employed which are directly connected at their inner ends to the fuse link 56 and fastened at their outer ends, as by screws 57, to the heads of the terminal caps or ferrules 58 that are applied over the open ends of the insulating shell or cartridge 59. In this construction a single disc or partition 60 having a fuse limiting or determining opening through which the fuse extends, is seated within said shell or cartridge. The operation of the springs to quickly separate the parts of a ruptured fuse link and the purpose of the determining opening is the same as in the constructions previously described. 120 125

The fuse links employed in the several constructions may be of any suitable or pre- 130

ferred form. Two designs or forms are illustrated in Figures 7 and 8. The fuse link 65 shown in Figure 7 comprises a thin, flat strip that is provided with numerous side notches 66, shown as of V shape to form connecting necks 67 which determine the load capacity of the fuse.

In Figure 8 the fuse link or strip is provided with a plurality of longitudinally spaced openings 69, shown as made circular, but may be made of other form. In this type of fuse link the effective cross section of the link to carry a current load is the sum of the width of the spaces 70 between the openings 69 and the edges of the strip.

These two forms of links, and others of equivalent construction which will be suggested thereby, have the common characteristics of numerous longitudinally and closely spaced, transversely narrow, load determining areas, thus providing greater safety and more positive regulation of the fusing temperature, due to any variations in the metal, than in other methods. Such numerous closely spaced current determining areas are especially valuable in connection with a link having means to maintain it under tensile stress and also because a fuse thus constructed, provided within the fuse chamber with a large number of drop-out sections, as will appear from an inspection of Figures 7 and 8 will permit a section of the fuse to drop-away from two fusing points relative

to the inner ends of the outer parts of the broken fuse.

35

It is to be understood that the feature of my invention relating to the quick separation of the parts of the fuse link at the sides of the rupture may be embodied in fuse structures differing specifically from that herein shown within the spirit and scope of the invention, as, for instance, to the low ampere fuse known as the Edison plug cut out or to the plural type embodying a number of fuses in a single cartridge. The invention is not, therefore, limited to the structural details illustrated, except as to the claim wherein such details are specifically set forth and as imposed by the prior art.

45

I claim as my invention:

An electrical thermal fuse comprising an open ended shell, conducting ferrules applied thereto, a fuse link attached at one end to one of said ferrules, a bushing within said shell for contact with one of said ferrules, a disc slideable in and filling said bushing, and a spring interposed between said disc and a shoulder on the bushing, said fuse link extending into said bushing, through the spring and through said disc and attached to the disc.

55

In testimony whereof I claim the foregoing as my invention, I hereunto append my signature at Chicago, Illinois, this 18th day of January, 1918.

BERTRAM J. GRIGSBY.
